UNITED STATES PATENT OFFICE.

GEORGE HALINKA, OF DETROIT, MICHIGAN.

VALVE-LOCK.

1,266,797.

Specification of Letters Patent.

Patented May 21, 1918.

Application filed October 8, 1917. Serial No. 195,298.

To all whom it may concern:

Be it known that I, GEORGE HALINKA, a citizen of the United States of America, residing at Detroit, in the county of Wayne 5 and State of Michigan, have invented certain new and useful Improvements in Valve-Locks, of which the following is a specification, reference being had therein to the accompanying drawings.

10 This invention relates to locks, and has special reference to a lock that may be advantageously used for controlling the fuel supply system of an automobile or other vehicle.

15 The primary object of my invention is to provide a permutation lock for holding a valve against operation, until the permutation lock is properly set to permit of the valve being actuated to supply fuel to a carburetor or engine. The lock has been designed for positioning on the dash of an automobile and provision is made so that the lock may be easily manipulated at night.

20 A further object of my invention is to provide a lock of the above type consisting of comparatively few parts that are durable, inexpensive to manufacture, easy to assemble, and highly efficient for the purposes for which they are intended.

25 The above and other objects are attained by a mechanical construction that will be hereinafter specifically described and then claimed, and reference will now be had to the drawings, wherein—

30 Figure 1 is a vertical sectional view of the lock;

Fig. 2 is a horizontal sectional view taken on the line II—II of Fig. 1; and

Fig. 3 is a front elevation of the lock.

35 Considering Figs. 1 to 3 inclusive, the reference numeral 1 denotes an automobile dash or other support having an opening 2 and mounted over said opening is a face plate 3 providing a cover for a rectangular casing 4 suitably secured to the dash 1 at the opening 2.

40 In the face plate 3 is mounted a permutation lock 5, said lock including a dial 6, an operating knob 7, and adjustable and interchangeable disks 8 having peripheral slots 9. The detail construction of the permutation lock is disclosed in Fig. 5 where it will be observed that the slotted disks 8 may be adjusted for various combinations.

45 Extending through the casing 4 is a fuel supply pipe 10 that may extend from a fuel

50 tank to the carburetor of an engine. The pipe 10, within the casing 4 has a conventional form of shut-off valve 11 and the stem 12 of said valve extends upwardly in the 60 casing and is journaled in a bracket 13. On the stem 12, adjacent the bracket 13, is a pinion 14, and meshing with said pinion is a rack portion 15 of a plunger 16 slideable in the face plate 3. By reciprocating the 65 plunger 16 the valve stem 12 may be rotated and the valve 11 turned off and on.

70 The pipe 10 within the casing 4 is supported and braced by brackets 17, and on the valve stem 12 is a pinion 18 normally 70 engaged by a rack bar 19 having pins 20 slideable in a slotted guide 21, carried by the inner side of the face plate 3. The rack bar 19 is slotted, as at 22 to receive one of the disks 8 of the lock 5, and when the slots 9 75 of said disks are out of alignment with each other and with the rack bar 19, said rack bar cannot be shifted, and consequently serves as a lock for holding the valve stem 12 against actuation by the plunger 16. 80 When the combination of the lock 5 is known and the disks 8 properly set with the slots 9 thereof providing clearance for the rack bar 19, then the valve 11 may be opened or closed through the medium of the plunger 16 and the rack and pinion.

85 In order that the lock 5 may be manipulated at night a small incandescent lamp 23 is located in proximity to the lock and in a shield or reflector 24 on the face plate 3. 90 The lamp 23 is in circuit with a switch 25, carried by the face plate 3, and a suitable source of electrical energy (not shown).

What I claim is:—

1. The combination with an automobile 95 dash, and a fuel supply pipe in proximity thereto and provided with a valve having a stem, of a face plate on said dash, a casing carried by said dash and coöperating with said face plate in inclosing the valve of said fuel pipe, a pinion on the stem of said valve, a rack engaging said pinion, a permutation lock carried by said face plate and having disks adapted to hold said rack against movement, and manually actuated means in 100 said casing operable through said face plate adapted for rotating said valve stem to open and close said valve when said rack is released by said lock.

2. The combination with an automobile 110 dash, and a fuel supply pipe in proximity thereto provided with a shut off valve hav-

ing a stem, of a pinion on the valve stem, a slotted rack bar engaging said pinion, means supporting said rack bar, a permutation lock carried by said dash and having 5 slotted disks adapted to hold said slotted rack bar against movement, and manually actuated means including a rack and pinion adapted for opening and closing said valve

when said rack bar is released by the disks of said lock. ¹⁰

In testimony whereof I affix my signature in the presence of two witnesses.

GEORGE HALINKA.
